Primary Examiner — George D. Kirschbaum*(74) Attorney, Agent, or Firm* — Dunlap Bennett & Ludwig, PLLC(57) **CLAIM**

The ornamental design for a wheel assembly, as shown and described.

DESCRIPTION

FIG. 1 is a front perspective view of the wheel assembly showing my new design;

FIG. 2 is a rear perspective view thereof;

FIG. 3 is a front elevation view thereof;

FIG. 4 is a rear elevation view thereof;

FIG. 5 is a left-side elevation view thereof, the right-side elevation view being a mirror image thereof;

FIG. 6 is a top plan view thereof;

FIG. 7 is bottom plan view thereof; and,

FIG. 8 is a clam shell exploded perspective view thereof. The broken lines shown in the drawings illustrate portions of the wheel assembly that form no part of the claimed design.

1 Claim, 7 Drawing Sheets(56)
